United States Patent Office

Des. 211,998
Patented Aug. 20, 1968

211,998

DESK-TYPE TELEPHONE

Ernst Abraham, Berlin, Germany, assignor to Krone
Kommanditgesellschaft, Berlin, Germany, a corpo-
ration of Germany

Filed Nov. 20, 1967, Ser. No. 9,469

Claims priority, application Germany May 18, 1967

Term of patent 14 years

(Cl. D26—14)

FIG. 1.

FIG. 2.

FIG. 3.

FIG. 4.

FIG. 5.

FIG. 6.

FIG. 7.

FIG. 8.

FIG. 1 is a front perspective view of the completely assembled desk-type telephone;

FIG. 2 is a front perspective view similar to FIG. 1 but with the hand set removed therefrom;

FIG. 3 is a front elevational view of the completely assembled desk-type telephone on a slightly reduced scale;

FIG. 4 is a rear elevational view of the desk-type telephone of FIG. 3 on a slightly reduced scale;

FIG. 5 is a side elevational view of the completely assembled desk-type telephone;

FIG. 6 is a side elevational view similar to FIG. 5 but with the hand set removed therefrom;

FIG. 7 is a top plan view of the completely assembled desk-type telephone; and

FIG. 8 is a top plan view similar to FIG. 7 but with the hand set removed.

The dominant features of my design reside in the portions shown in full lines.

I claim:

The ornamental design for a desk-type telephone, as shown and described.
